ROBERT T. JOHNSTON, OF SCOTCH PLAINS, NEW JERSEY, ASSIGNOR TO R. HOE AND CO., OF NEW YORK, N. Y., A CORPORATION OF NEW YORK.

PLATE FINISHING AND COOLING MACHINE.

1,409,182.

Specification of Letters Patent. Patented Mar. 14, 1922.

Application filed September 6, 1918. Serial No. 252,889.

To all whom it may concern:

Be it known that I, ROBERT T. JOHNSTON, a citizen of the United States, residing at Scotch Plains, county of Union, and State 5 of New Jersey, have invented certain new and useful Improvements in Plate Finishing and Cooling Machines, fully described and represented in the following specification and the accompanying drawings, forming 10 a part of the same.

This invention relates to certain improvements in devices for cooling curved stereotype plates, and the invention has for its especial object the production of a compact, 15 small-sized device for cooling plates, which may be used in connection with or as a part of a plate finishing machine, in which the plates are cooled in a vertical position, so as to economize in the space required for 20 the manipulation of the plates.

It is a further object of the invention to provide a machine in which the plates are cooled and delivered in a manner to economize space as far as possible and so that the 25 plates may be conveniently handled by the operator.

For a full understanding of the invention it will now be described in connection with the accompanying drawings, in which,—

30 Fig. 1 is a side elevation, partly broken away and partly in section, of the device, showing a plate received from a finishing mechanism and about to be turned from horizontal to vertical position.

35 Fig. 2 is a view similar to Fig. 1, showing a plate being cooled, and a cooled plate delivered.

Fig. 3 is a plan view of the construction shown in Fig. 2.

40 Fig. 4 is a detail view partly broken away, illustrating a conventional movement for intermittently moving the carrier.

Referring now to these drawings, the plate p to be cooled is fed to the turning 45 mechanism in any suitable manner. In the construction illustrated, the plate is fed from a finishing mechanism consisting generally of a finishing cylinder 1, mounted in bearings 2, in a frame 3 of the machine, this

50 frame being supported in any suitable manner (not shown).

To produce a machine occupying a minimum of space, the plate is cooled and delivered in a vertical position, and preferably 55 the plate is fed to the delivering means and

cooled while thereon. Means are further provided for turning or tipping the plate from a horizontal position in which it is fed to the turning mechanism, to a vertical position, in which it is cooled and delivered. 60

While the particular means employed for effecting this may be widely varied, in the particular construction illustrated, there is provided a table 4 having side guides 5, 6, to which table a plate is fed on its straight 65 edges, it being fed, as shown in Fig. 1, from a finishing mechanism. This table 4 is given a downward movement to turn the plate from its horizontal to a vertical position. In the particular construction illustrated, 70 the table is supported from a rock shaft 7 suitably mounted in bearings 8 in the frame 3 of the machine. This rock shaft is operated to lower the table to deliver a plate and to raise it in plate-receiving position by 75 means of an arm 9 on the shaft to which is connected a crank arm 10 operated from a crank 11 on a driven shaft 12, suitably mounted in the frame of the machine, the shaft being driven from any suitable source 80 of power, (not shown).

The table is periodically operated from the crank connections to gradually lower the plate, as shown in Fig. 2, and to cause it to assume an upright or vertical position, 85 in which the plate is cooled, the plate being deposited by the table onto a suitable support for cooling. In the best construction, the plate will be deposited to a support by which it may be delivered after cooling. 90 The means for effecting this may be varied. As illustrated, the plate is deposited by the table onto a travelling carrier 13. This carrier may vary in construction, but as shown includes a pair of side chains 14, 15, 95 to which are connected supporting bars 15'. The carrier chains pass over pairs of sprockets 16, these sprockets being carried on shafts 17.

The table is as shown in Figs. 1 and 2 100 formed with a front lip against which the edges of the plate abut, this lip keeping the plate from sliding off the table as the table is gradually lowered from the horizontal position of Fig. 1, to the delivering position 105 of Fig. 2. As the table is lowered gradually the plate gradually approaches the carrier and is gradually delivered there on, and when the parts are in the position shown in Fig. 2 the holding lip of the table is so 110

2
positioned relatively to the carrier that the plate may be taken off the table by the carrier and removed.

The carrier is given an intermittent travelling movement by suitable mechanism, so that the plate is stopped, cooled and then forwarded for delivery.

A conventional mechanism for effecting this intermittent movement is shown in Figure 4, in which there is shown a star wheel 21 mounted on one of the sprocket shafts 17 before referred to, this wheel being provided with operating notches 22 and holding faces 23. This star wheel is operated by a roller 24 on an arm 25 carried on a shaft 26 to which power may be applied in any suitable manner, a segmental locking plate 27 being provided, which cooperates with the locking faces of the star wheel, this locking plate being carried on the shaft 26. This mechanism is a usual one for effecting intermittent travelling movement in a carrier, and in itself forms no part of the present invention.

25. The cooling devices employed for cooling the plate may be of any suitable character. Preferably they will be such as to cool the plate by direct contact therewith with a cooling fluid. As illustrated, there are provided a pair of pipes 18, 19, supported in any suitable manner so as to direct a supply of water against the inside and the outside of the plates as the plates stand on the carrier.

35. With the machine shown, a very compact mechanism is provided for cooling the plates and one which can be used in combination with a finishing mechanism, with great economy in space in the stereotype room,

which is important. While the particular construction shown and described is preferred; it will be understood that various changes and variations may be made in the details of this construction without departing from the invention.

45. What is claimed is:

1. In a stereotype plate cooling and delivering device, the combination of a finishing mechanism, a table having a fixed front stop to which table a plate is fed from the finishing mechanism in a horizontal position, a travelling carrier arranged adjacent the table, means for gradually lowering the table with a plate thereon to turn the plate from a horizontal to a vertical position and deposit it on the carrier free of the front stop, and means located adjacent the carrier for directing a supply of cooling fluid against both the inner and outer surface of the plate.

2. In a stereotype plate cooling and delivering device, the combination of a finishing mechanism, a table including side guides and a fixed front stop to which table a plate is fed from the finishing mechanism in a horizontal position, a carrier and means for giving it an intermittent movement located below the adjacent table, means for gradually lowering the table with a plate thereon to turn the plate from a horizontal to a vertical position and deposit it free of the stop on the carrier in a vertical position, and means located adjacent the carrier for directing a supply of cooling fluid against the surface of the plate.
